United States Patent Office

Des. 217,827
Patented June 16, 1970

217,827

SALAD DISH

John B. Parker, Sr., Rte. 1, Box 253,
Eden, N.C. 27288

Filed Aug. 12, 1969, Ser. No. 18,655

Term of patent 14 years

Int. Cl. D7—01

U.S. Cl. D44—10

FIG. 1

FIG. 2

FIG. 3

FIG. 4

In the drawing:

FIG. 1 is a front perspective view of a salad dish embodying my design;
FIG. 2 is a top plan view, slightly reduced, of FIG. 1;
FIG. 3 is a left side elevational view of FIG. 2; and
FIG. 4 is a right side elevational view of FIG. 3.

I claim:

The ornamental design for a salad dish, as shown.
